United States Patent

Des. 238,463
Patented Jan. 20, 1976

238,463

TOILET TISSUE HOLDER

Arthur E. Bauman, 764 Johnston St.,
Akron, Ohio 44306

Filed Nov. 1, 1973, Ser. No. 411,905

Term of patent 14 years

Int. Cl. D23—02

U.S. Cl. D6—97

FIG. 2

FIG. 1

FIG. 1 is a perspective view of a toilet tissue holder showing my new design.

FIG. 2 is a perspective view of a second embodiment of the design of FIG. 1.

I claim:

The ornamental design for a toilet tissue holder, substantially as shown and described.
